(57) **CLAIM**

The ornamental design for an inside the waistband carriage system, as shown and described.

DESCRIPTION

FIG. 1 is an isometric view of an inside the waistband carriage system in accordance with the present invention, wherein a magazine for a firearm and a tourniquet are secured therein;

FIG. 2 is an isometric view of the inside the waistband carriage system shown in FIG. 1 without a magazine for a firearm or a tourniquet secured therein;

FIG. 3 is a rear view of the inside the waistband carriage system shown in FIG. 2;

FIG. 4 is a top view of the inside the waistband carriage system shown in FIG. 2;

FIG. 5 is a front view of the inside the waistband carriage system shown in FIG. 2;

FIG. 6 is a right side view of the inside the waistband carriage system shown in FIG. 2;

FIG. 7 is a left side view of the inside the waistband carriage system shown in FIG. 2; and,

FIG. 8 is a bottom view of the inside the waistband carriage system shown in FIG. 2.

The portions of the inside the waistband carriage system shown in broken lines with shorter segments are for illustrative purposes only and form no part of the claimed design. In FIG. 1, the magazine for a firearm and the tourniquet shown in broken lines with shorter segments are for illustrative purposes only and form no part of the claimed design. The portions of the inside the waistband carriage system shown in broken lines with longer segments represent stitching.
